(57) **CLAIM**

The ornamental design for an optical connector with a shutter, as shown and described.

DESCRIPTION

FIG. 1 is a front view of an optical connector with a shutter of the present invention;

FIG. 2 is a rear view thereof;

FIG. 3 is a right side view thereof;

FIG. 4 is a left side view thereof;

FIG. 5 is a top view thereof;

FIG. 6 is a bottom view thereof;

FIG. 7 is a cross-sectional view taken along lines VII—VII of FIG. 1;

FIG. 8 is a cross-sectional view taken along lines VIII—VIII of FIG. 1;

FIG. 9 is a view of FIG. 7 with a cable plug inserted; and, FIG. 10 is a perspective view of the optical connector of FIG. 1.

The broken line showing of the environment is for illustrative purposes only and forms no part of the claimed design.
